ABSTRACT

A control system and method for the ignition and fuel system of an internal combustion engine of a vehicle in which certain operating conditions of the engine and vehicle are sensed and converted into coded information which can be processed by the computer controlling the system.

CONTROL METHOD FOR INTERNAL COMBUSTION ENGINES

This invention concerns a control method for internal combustion engines, particularly for car engines.

It is known that improvements can be made in the riding comfort, safety, performance, and pollution control of motor vehicles by the use of electronic circuits. These circuits are used to check and/or to control, the operation of certain elements, or to inform the driver of the vehicle about the respective conditions of such elements. These circuits use techniques which are generally known in the field of information or industrial process computers.

In vehicles equipped with an electronic control system, the "computer" receives information in various forms from sensors which constantly monitor the operating conditions of the vehicle or of a certain part of the vehicle. Starting from this information produced by the sensors, one can work out a complex function depending on the variables sensed by the sensors to control elements of the vehicle or simply to make the value of the said function visible or audible to the driver. In either case, it is frequently advantageous to use numerical (i.e. digital) techniques, which can now be readily processed due to the existence of integrated circuits.

The object of the invention is to provide a simple system for producing information supplied by the sensors in numerical, that is in coded digital form and ways to transform and utilize this coded information.

The present invention concerns a control method and system for internal combustion engines and is characterised in that the coded information supplied by the sensors measuring physical operating quantities of the engine are produced at a certain frequency, the so-called sampling frequency. The coded information is produced in the form of a number of word segments comprising a limited number of digits and the means value of several samplings of the word segments is representative of the mean value of the corresponding physical quantity, since the word segments are grouped to form a complete first word. The first word is converted by a programmed memory into a second word and the second word is converted by a transformation circuit into a function whose mean value is representative of the mean value of a desired regulating function. This regulating function is converted into a control quantity for the engine.

Other characteristics of the invention will become apparent from the following description with reference to the attached drawings where:

FIG. 1 shows a schematic diagram of a circuit for forming the sampling frequency and the signals at various points of the circuit;

FIG. 2 shows a schematic diagram of a coding circuit for a frequency measurement with interpolation and displacement of zero in the case where the sampling frequency is lower than the measured frequency;

FIG. 3 shows a schematic diagram of a coding circuit for a frequency measurement to eliminate the stroboscopic effect in the case where the sampling frequency is of the same order of magnitude as the measured frequency;

FIG. 4 shows a schematic diagram of a frequency measuring circuit for retention of the first numbers of the measured quantity;

FIG. 5 shows a schematic diagram of a circuit for forming a sawtooth signal and its utilization with a comparator;

FIG. 6 shows a schematic diagram of a circuit for producing a numerical code in response to a voltage;

FIG. 7 shows a schematic diagram of a circuit for forming a linear function;

FIG. 8 shows a schematic diagram of a circuit for the formation of a linear function from coded information;

FIG. 9 shows a schematic diagram for forming the mean value of a linear function in a numerical form;

FIG. 10 shows a schematic diagram of a circuit for transforming a voltage into a time duration;

FIG. 11 shows a diagram of the arrangement of a speed sensor (11a), of the structure of the sensor (11b), and (11c) of a circuit, incorporating this sensor, for forming a doublefrequency signal;

FIG. 12 shows a schematic diagram of a circuit for forming two signals in the particular case of ignition control of the engine;

FIG. 13 shows a block diagram of a complete circuit for system and method according to the invention;

FIG. 14 shows a schematic diagram of a circuit for numerical counting used for measuring a physical quantity by sampling;

FIG. 15 is a timing diagram of a circuit for converting a linear into a non-linear function;

FIG. 16 shows a curve representing the variation of the cyclical ratio in accordance with one embodiment of the invention;

FIG. 17 shows a curve representing the variations of the cyclical ratio according to another embodiment of the invention;

FIG. 18 shows a schematic diagram of a simplified electronic circuit for the formation of the function represented in FIG. 3; and

FIG. 19 shows a diagram of output signals of the circuit of FIG. 18 for the different values of the cyclical ratio.

Within the framework of the invention, the signal supplied by a sensor is translated into a numerical (digital) form. The sensors used in an automobile or other vehicle are of different type and of different nature. They translate their measurements in the form of a variation of a measured electric quantity. This information can exist directly in numerical digital form, for example, the position of an element provided with a digital encoder. This type of sensor does not present any particular problems.

The information can also be represented by pulses of variable frequency called, for example, f_r . This is the case, for example, in a sensor of the type detecting the proximity with regard to a gear provided with teeth. In this case we measure, as shown in an example below, either the frequency of the pulses or their repetition cycle. We will generally choose these among two possibilities, depending on the respective problem and particularly on criteria discussed below.

If it is necessary, as it frequently happens, to form the mean value of an electrical signal to represent the mean value of a physical quantity varying about a given position, it is advisable, if the operation is to be representative, that the response of the sensor be linear.

The signal of the sensor can also be in the form of a voltage. In this case we can proceed by using known voltage-frequency converters, for example, to periodically compare the sensor voltage with a variable (saw-

tooth) voltage and measure the number of pulses supplied by a clock, while the sensor voltage is lower (or higher) than the reference voltage. This is a technique which is well known, for example, for use in electronic voltmeters.

Finally, the sensor can deliver its information in the form of variations of a resistance, inductance or electric capacitance. These variations can be easily transformed into variations of voltage or pulse frequency.

The part of the computer provided for the acquisition of data from the sensors must furnish periodically at a given frequency, called the sampling frequency, coded information in the form of digits such that the mean value determined after a sufficient number of samplings is representative of the mean value of the physical input quantity to the sensor.

Referring to FIG. 1, which shows a circuit for controlling the sampling frequency, the quantity or quantities from the sensors are measured during a time T . The time T is obtained, for example, by dividing pulses produced by a clock circuit H .

The clock H directs pulses of a frequency $1/T_1$ to a divider 1 whose intermediate outputs are represented by $A_1, A_2 \dots A_{n-1}$. At the output A , the frequency of the pulses is equal to the clock frequency, divided by 2ⁿ.

By means of the "AND" gates 2, 3 and 5 and of an inverter 4 connected to the clock and the divider the following quantities are formed at the gate outputs:

$$S_1 = A_{n-1} A_{n-2} \dots A_3 \cdot A_2$$

$$S_2 = S_1 \cdot A_1 \cdot H$$

$$S_3 = S_1 \cdot \bar{A}_1 \cdot H \quad (\bar{A}_1 \text{ is the inverted state of } A_1).$$

The sampling period is, for example, $T = 2^{(n-1)} T_1$, which is found in the S_1, S_2 or S_3 outputs, as indicated in the diagram adjoining FIG. 1.

Measurement of a frequency.

The measurement of a frequency, produced as previously described, is simple. It suffices to count, for example, how many pulses are produced by the quantity being measured as expressed by a frequency during the time T .

If we take into account the conditions listed above, the problem becomes more complex.

In order to facilitate the understanding assume, for example, that the frequency of the clock pulses from H is 1 mHz ($T_1 = 10^{-6}$ seconds). Assume further that we have effected a division by $2^9 (n = 10)$, that is, $T = 512$ microseconds (the division by a power of 2 is not obligatory). Finally, assume that a pulse frequency to be measured varies between 0.4 and 0.8 MHz.

If the method described above is applied, the number of pulses counted will be between:

$$0.4 \times 10^6 \times 5.12 \times 10^{-4} = 204.6 \text{ pulses and}$$

$$0.8 \times 10^6 \times 5.12 \times 10^{-4} = 409.6 \text{ pulses.}$$

We realize then that a counter with at least 9 digits ($2^9 = 512$) is required to count the number of pulses received with an accuracy of 1 pulse. The counter will always have to start at at least 204.

In order to eliminate this inconvenience, a circuit according to FIG. 2 is used. Element 2.1 is a NAND gate as is 2.5. Element 2.4 is an AND gate while elements 2.2, 2.3 and 2.6 are binary counters. Element 2.7 is a transfer unit, such as a buffer storage register which can store the count operation of the circuit of FIG. 2 as described as follows. The gate 2.1 forwards the pulses whose frequency f_x is to be measured during a time $T = 2^{(n-1)} T_1$, which, is less than a time "A2 high",

that is, in the highest example $512 - 2 \times 1 = 510$ microseconds. It follows that during a sampling time, N pulses with N between $0.4 \times 5.12 \times 10^2 = 204$ and $0.8 \times 5.12 \times 10^2 = 409$ pulses will pass through gate 2.1.

The counter 2.2 is connected as a divider to divide by D so that the number of pulses leaving 2.2 and entering counter 2.3 and gate 2.5 is N/D . These pulses are applied to counter 2.3 and the outputs of certain stages of 2.3 are applied to the inputs of AND gate 2.4, so that the output of 2.4 is high only when the outputs from 2.3 appearing at the input of 2.4 are all high, that is, when 2.3 has counted a certain number of pulses. The output of AND 2.4 is applied back to a special input of 2.3, which blocks the counter when the certain count is reached, and also to gate 2.5. The pulses from counter divider 2.2 thus traverse gate 2.5 to counter 2.6, only when counter 2.3 has attained the value fixed by the selection of its outputs which are connected to AND 2.4.

At the end of the sampling period T , 2.6 marks a number N_A :

$$N_A = D/N - n, \text{ if } n \text{ is the number selected by the output coding of 2.3 applied to AND 2.4}$$

Assume, for example, that $D = 100$ and f_x is 0.4 MHz so that $N/D = 2.04$.

This indicates that two pulses are produced by counter 2.2 during T and that at the end of T counter 2.2 has counted 4. If we assume that $n = 2$, this means that at the end of T , if all counters were at zero at the start, the situation would be as follows:

	number of pulses	204
counter 2.2 at the end of T	4	
counter 2.3 at the end of T	2	
counter 2.6 " " " "	0.	

Let us assume that the cycle starts again after it has been effected by S_2 (see FIG. 2) applied to the suitable inputs of the counters 2.6 and 2.3 from the circuit of FIG. 1 during the time S_1 but without resetting counter 2.2 to zero.

At the end of the second sampling we have then:

$$2.2 \rightarrow 8$$

$$2.3 \rightarrow 2$$

$$2.6 \rightarrow 0$$

At the end of three samplings we have

$$2.2 \rightarrow 12$$

$$2.3 \rightarrow 2$$

$$2.6 \rightarrow 0$$

and so forth, at the end of 25 samplings we have:

$$2.2 \rightarrow 0$$

$$2.3 \rightarrow 2$$

$$2.6 \rightarrow 1$$

This means that the device of FIG. 2 performs two operations:

1. it interpolates the values

2. it eliminates the numbers below a certain value, and if we want, it displaces the zero value of the input pulses.

In other words, the circuit of FIG. 2 is suitable to produce an output count of 0 for N less than 200, an output count of 1 for $N = 300, \dots$ an output count of 4 for $N = 700$.

If a value of N is between 200 and 300, 204 for example, the output counter 2.6 marks for $(x+y)$ samplings, x times 0 and y times 1, so that

$$\frac{V}{x+y} = 0.04$$

that is, the interpolation is effected simply by the frequency of two numbers surrounding the value of N , so that the numerical value is equal to the coded value which would have to be attributed to N .

Buffer 2.7 receives signal S_3 from the circuit of FIG. 1 and under the order from S_3 transfers in each cycle the value received at its inputs to its outputs for further use. The circuit of FIG. 2 permits the elimination of useless numbers (saving of digits) and also the interpolation between values, provided the frequency of f_x is high relative to the sampling frequency. If the latter is not the case, the circuit of FIG. 3 is used.

The circuit of FIG. 3 can perform operation similar to those of the circuit of FIG. 2, but on the theory that the frequency f_x to be measured is not very high compared to the sampling frequency. The problem is then that in order to know the value of the frequency f_x , it suffices in principle to count the pulses during a sufficient period of time to obtain the desired accuracy. In the case of a computer for vehicles, it is desirable to know at a relatively high frequency the values close to the frequency to be measured so as to be able to express it by a number counting a few digits. The measurements are made so that the mean value of the displayed values is equal to the measured value. Taking into account these conditions, we can accept, as in the case of the circuit of FIG. 2, a period for resetting to or holding at zero during which there is no counting. In fact, there is a risk of ending up with a wrong result, due to the "stroboscopic effect." If the frequency to be measured, is, for example, equal to 4 times the sampling frequency, the counter will have an output count of 3 or 4, depending on the relative phase of the sampling scale and of the pulses of f_x . A solution consists in counting the pulses f_x constantly.

The operation of the circuit of FIG. 3 is described below. The pulse at the start of the sampling (S_1) is applied to one of the inputs of a flip-flop circuit (RS type) 3.1, which has the effect of bringing the output of 3.1 connected to one of the inputs of an AND gate 3.6 to the high level. This also has the result that the complementary output of 3.1, connected to an input of an AND gate 3.5, is brought at the same time to the low level. The pulses f_x arrive at the other inputs of gates 3.5 and 3.6. This has the result that when 3.1 flips into "operating" position at the start of the appearance of S_1 , the f_x pulses can pass through gate 3.6 in this condition, while they are blocked from passing through gate 3.5. The appearance of a pulse f_x is thus transmitted to a flip-flop (RS type) 3.3 through gate 3.6 and changes this flip-flop circuit into the operating state. The output of flip-flop 3.3 connected to one of the input of an AND gate 3.4 goes high.

To the other input of gate 3.4 is applied $\bar{S}_1$ (S inverted) by an inverter 3.2, so that the output of gate 3.4 goes high when:

- its input connected to 3.3 is high, that is, when the pulse f_x from gate 3.6 has been counted
- its input connected to $\bar{S}_1$ is high, that is, during the "dead" time of S_1 .

The output of gate 3.4 is connected to the zero reset inputs of flip-flops 3.1 and 3.3 to cause the flipping back of 3.3 and 3.1 to the opposite states this causes

the opening of the gate 3.5 and closing of gate 3.6. A counter 3.7, AND gates 3.8 and 3.9, counter 3.10 and buffer 3.11; are elements respectively corresponding to 2.3, 2.4, 2.5, 2.6 and 2.7 of FIG. 2 with the same functions, (elimination of the pulse count below a selected number) of counting and resetting to zero (by S_2), and data transfer (by S_3). By a suitable arrangement of inputs and polarities, the circuit elements of FIG. 3 can be so arranged that the flipping of 3.3 is counted or not.

- If it is not counted, we obtain directly the elimination of the first number. The counting by the circuit of FIG. 3 is permanent, the counting element is generally 3.10. During the dead time of S_1 , or $\bar{S}_1$, and until the first f_x pulse following the start of S_1 , the counting element (of 15) 1) consists of 3.3 (and 3.1). This presupposes naturally that the time when S_1 is high is smaller than the minimum period of f_x , which is practically always the case (low frequency of f_x). In the opposite case, we can replace 3.3 by AND gate 3.9 and count several pulses before "opening" the principal counter 3.10.

FIG. 4 shows a circuit which is simpler than that of FIG. 3 and which performs a similar function. A flip-flop circuit 4.1 (RS type) receives at its "working" input the signal S_1 which makes the output connected to an AND gate 4.2 go high and the output connected to an AND gate 4.7 go low. This has the result that the pulses f_x can pass gate 4.2 and not 4.7. Element 4.3 is a counter similar to 2.3 and blocks the first pulses below a selected number. When, after the start of sampling, a number of pulses equal to that selected and coded by counter 4.3 and an AND gate 4.4 (as explained for elements 2.3, 2.4 in FIG. 2) has traversed gate 4.2, the output gate of 4.4 goes high. This has the effect of returning flip-flop 4.1 into its rest condition and consequently of blocking gate 4.2 and opening gate 4.7. The counting is continued then by a counter 4.5 which has been reset during S_1 to zero by signal S_2 . The count of 4.5 is transferred to a buffer 4.6 and it is outputted from 4.6 by the S_3 signal.

Measurement of a voltage

The measurement of a voltage from a sensor is effected by counting pulses during a given time, such as the linear portion of a sawtooth wave. A circuit for accomplishing this is represented in FIG. 5.

The signal S_1 is applied to the base of a transistor 5.6 to discharge a capacitor 5.2 which is connected between the transistor collector and its emitter. Capacitor 5.2 is recharged through a resistor 5.5 and is connected across the inverted input (-) and the output terminal of an operational amplifier 5.1. The non-inverting input (+) of the amplifier is biased by a voltage divider 5.3, 5.4. This well-known circuit produces a highly linear sawtooth at the output of 5.1.

55 The sawtooth voltage is compared by a comparator 5.7 with the amplitude of the voltage to be measured. The output of 5.7 is low, while the sawtooth voltage is higher in amplitude than the voltage to be measured, and the output is high in the opposite case.

60 If the sawtooth voltage is designated by V_d , then V_d is translated from the end of the S_1 by the expression

$$V_d = V_{do} - kt$$

where V_{do} and k depend on 5.3, 5.4 and 5.5.

The flipping time of comparator 5.7 is such that

$$V_x = V_{do} - kT,$$

where

$$T_e = (V_{do} - V_x)/k$$

The measuring time is, for example, the sampling time minus S_1 and T_e , hence in the case described above,

$$2^{(n-1)}T_1 - 2T_1 - T_e = A + BV_x$$

where A and B are constants.

The circuit of FIG. 6 is similar to that of FIG. 2 and shows the measuring arrangement. The output of comparator 5.7 is applied to an AND gate 6.1. When the output of comparator 5.7 is high (after flipping of the comparator) and S_1 is low, $\bar{S}_1$ being applied to AND gate 6.1, the gate 6.1 forwards the clock pulses H to a counter 6.2. The pulses are counted by 6.2, which reduces the number (interpolation or division) and transmits them to another counter 6.3 which is programmed by a gate 6.5, as explained above, for 2.4 for the elimination of the pulse count below a certain number. This permits, once the certain number is reached a counter 6.7 to count the pulses transmitted by 6.2 when a gate 6.4 has become conditioned to pass signals by counter 6.3 and gate 6.5. At the end of the cycle (S_1 high), the counting is stopped since 6.1 is closed. S_2 resets counters 6.3 and 6.7 to zero. S_3 ensures the transfer of data from the buffer register 6.8. Counter 6.2 is not reset to zero for the reasons indicated above.

Decoding — utilization.

With the means indicated above we can transform the signals supplied by one or more physical quantity sensors into one or several numbers, which generally vary with each sampling, so that the mean value represents the value of the measured physical quantity. As a result, each quantity is expressed at the end of each sampling by a binary number which comprises, as required, a given number of digits.

To facilitate the understanding of the invention, assume that we want to form a regulating function depending on four variables L M N ϕ . Assume that the quantity L is expressed by 3 binary bits (8 possible numbers), the quantity M by 4 bits (16 possible numbers), M by 2 bits (4 possible numbers) and ϕ by 1 bit (2 possible numbers). This means that the result of the sampling can be written in the form of a binary number with $(3 + 4 + 2 + 1) = 10$ bits, or

$$L_1 L_2 L_3 M_1 M_2 M_3 M_4 N_1 N_2 \phi$$

where the values L_1, M_1, N_1, ϕ are 0 or 1. The first word segment consists of $L_1 L_2 L_3$, the second word segment of $M_1 M_2 M_3 M_4$, the third word segment of $N_1 N_2$ and the fourth of ϕ .

0 1 1 0 0 1 1 0 1 means that for this "word" we have the variable L with a numerical value of 3. 50 have the variable M with a numerical value 9 have the variable N with a numerical value 2 have the variable ϕ with a numerical value 1

The total number of "possible" words is $8 \times 16 \times 4 \times 2 = 1,024 = (2^{10})$.

According to a well-known technique of programmed memories, we can associate with each of these 1,024 words a number which is representative of the value which we want to give the function of L M N ϕ , at the "point" under consideration. The word point is here understood in a broad sense, because we are evidently not dealing here with a geometric point, since it has five dimensions.

In the course of the sampling the word varies if each quantity does not correspond exactly to a "fixed value" of L M N ϕ , which corresponds to the interpolation function explained above. It follows that the associated value varies likewise since its mean value is equal to the

mean value of the linear form as a function of L M N ϕ passing through fixed points.

To facilitate the understanding, we assume that L is between L_i and L_{i+1} , M between M_j and M_{j+1} , N between N_k and N_{k+1} , and ϕ between ϕ_1 and ϕ_2 .

If we designate with Σ_L the quantity

$$\frac{L - L_i}{L_{i+1} - L_i}$$

and designate

$$\Sigma_M = \frac{M - M_j}{M_{j+1} - M_j},$$

etc.

then the weight of the quantity $F_{i, j, k, l}$ associated with L_i, M_j, N_k and ϕ_2 is:

$$(1 - \Sigma_L) \cdot (1 - \Sigma_M) \cdot (1 - \Sigma_N) \cdot (1 - \Sigma\phi)$$

That of $F_{i+1, j+1, k+1, l+1}$ is $(\Sigma_L \Sigma_M \Sigma_N \Sigma\phi)$. That of $F_{i+1, j, k+1, l}$ as $\Sigma_L (1 - \Sigma_N) \Sigma_K (1 - \Sigma_1)$ and so forth.

The mean point of the function F, an associated function, is the barycenter of these points having the indicated loads.

These numbers F are expressed by a binary code comprising the digits defined by the accuracy to be obtained, namely, $X_1, X_2, \dots, X_f$. If f is the selected number of digits, X_1 is the highest load digit, and X_f the lowest load digit.

Decoding

The formation of a linear voltage is described. We assume that f is less than $(n-1)$, the number of pulse train outputs of the divider 1 of the circuit of FIG. 1. If this is not the case, we can always add one or more elements to the circuit of FIG. 1, and use only $(n-1)$ to form the sampling time indicated above.

We form the quantity:

$$S = \bar{A}_1 X_1 + A_1 \bar{A}_2 X_2 + A_1 A_2 \bar{A}_3 X_3 + \dots + A_1 A_2 \dots \bar{A}_f X_f$$

$$= a_1 X_1 + a_2 X_2 + a_3 X_3 + \dots + a_f X_f.$$

In the course of a sampling, the value of the cyclical ratio high/(high + low) of this function is representative of F and independent of the frequency.

To facilitate the understanding, we assume that we have

$$f = 8 \text{ and } n-1 = 9.$$

In the course of a sampling period the quantity is:

$$a_1 = \bar{A}_1 \text{ is 256 times high and 256 times low}$$

$$a_2 = A_1 \bar{A}_2 \text{ is 128 times high while } a_1 \text{ is low}$$

$$a_3 = A_1 A_2 \bar{A}_3 \text{ is 64 times high, while } a_1 \text{ and } a_2 \text{ are low}$$

$$a_4 = A_1 A_2 A_3 \bar{A}_4 \text{ is 32 times high, while } a_1, a_2, \text{ and } a_3 \text{ are low}$$

$$a_5 = A_1 A_2 A_3 A_4 \bar{A}_5 \text{ is 16 times high, while } a_1, a_2, a_3 \text{ and } a_4 \text{ are low}$$

$$a_6 = A_1 A_2 A_3 A_4 A_5 \bar{A}_6 \text{ is 8 times high while } a_1, a_2, a_3, a_4 \text{ and } a_5 \text{ are low}$$

$$a_7 = A_1 A_2 A_3 A_4 A_5 A_6 \bar{A}_7 \text{ is 4 times high while } a_1 \text{ through } a_6 \text{ are low}$$

$$a_8 = A_1 A_2 A_3 A_4 A_5 A_6 A_7 \bar{A}_8 \text{ is 2 times high while } a_1 \text{ through } a_7 \text{ are low}$$

It follows that the ratio of the high signal to the total sampling time of S is

$$R_S = \frac{256X_1 + 128X_2 + 64X_3 + 32X_4 + 16X_5 + 8X_6 + 4X_7 + 2X_8}{512}$$

or

$$R_S = \frac{1}{2}X_1 + \frac{1}{4}X_2 + \frac{1}{8}X_3 + \frac{1}{16}X_4 + \frac{1}{36}X_5 + \frac{1}{64}X_6 + \frac{1}{28}X_7 + \frac{1}{256}X_8$$

with $X_1 \dots X_8 = 0$ or 1.

We can thus write $R_S = (2F/512)$. This means that the value of sampled F is expressed 2 times per sampling time T. If we had on the other hand $f = n-1$, a single exploration would correspond to each sampling.

Since we are dealing here with a cyclical ratio, this value is independent of the clock frequency and of the sampling frequency.

FIG. 7 shows the circuit of a decoder. The circuit, uses by way of example, only the NAND gates. The first gate forms the quantity: $\bar{A}_1 \bar{X}_1 = \bar{a}_1$. The second gate forms the quantity: $\bar{A}_1 \bar{A}_2 \bar{X}_2 = \bar{a}_2$. The 8th gate forms the quantity: $\bar{A}_1 \bar{A}_2 \dots \bar{A}_8 \bar{X}_8 = \bar{a}_8$. The final gate forms: $\bar{a}_1 \bar{a}_2 \dots \bar{a}_8 = a_1 + a_2 + \dots + a_8 = S$. In order to obtain an analogous voltage representation of F, it suffices therefore to place at the output of S a filter (passive or active) of the RC-type. Other method of forming the voltage. FIG. 8.

Another example of a decoding circuit for forming a voltage from the code recorded in a memory is shown in FIG. 8. To facilitate the understanding of the foregoing considerations, we assume that the problem consists here too in expressing in the form of a voltage the mean value of a regulating hypersurface depending on 4 parameters L M N ϕ , translated at each moment by a code with several digits X_i . By any or several of the methods described above for sampling information, we direct at each moment numbers L M N ϕ to the inputs of a programmed memory 8.1. The system can be arranged without a "latches" circuit, or buffer, such as 2.7, 3.11, 4.6 or 6.8, between a number representative of the measuring state of one of the quantities and the memory.

To show this method of forming the circuit, there is represented in FIG. 8(b) an arrangement, assuming for example, that the translated quantity L is measured by means of a circuit, such as that of FIG. 6. The quantity M by a circuit such as that of FIG. 4, the quantity N by a circuit such as that of FIG. 3 and the quantity ϕ by a circuit such as that of FIG. 2. This choice is simply made by way of illustration. Also assume that the counting capacity of these circuits has been necessarily limited by the choice of the counters.

Blocks 6.7, 4.5, 3.10 and 2.6 represent the circuit elements of FIGS. 6, 4, 3 and 2 respectively from which the connections are made to the programmed memory 8.1. This means that these elements have been connected directly to 8.1, eliminating the buffers 6.8, 4.6, 3.11 and 2.7 respectively.

In this arrangement the bits L1 change continually during sampling at the inputs 8.1.10 to 8.1.19 of the programmed memory 8.1. This produces variations at the outputs X_i of the memory 8.1, called the "code gate". In fact, the outputs X_i of 8.1 are connected to the inputs of a preselection counter 8.2. The outputs of this counter are connected to a NAND gate 8.3. The counter 8.2 also receives a transfer signal at another of its input, called the "charge input" 8.9, with each pulse at the end of the sampling, such as signal S_3 described above. When all the inputs of gate 8.3 are "high", the output at 8.7 is low, which has the result that the clock

pulses H applied to the input 8.5 of a NAND gate 8.4

can arrive at the counting input 8.8 of 8.2. The second input 8.6 of 8.4 is low in this case and the output of 8.4 is therefore always high. On the other hand, if at least one of the outputs of 8.2 is low, the output of 8.7 is high and consequently 8.4 forwards the clock pulses H to 8.8 and the counter 8.2 can count.

The method of operation of the circuit of FIG. 8 is described as follows. When the brief transfer pulse S_3 is applied to 8.9, the counter 8.2 "is charged" to a number n, such as:

$$n = 2^7 \cdot X_1 + \dots + 2^0 \cdot X_8.$$

This represents exactly the value of the sampling at the time of measurement.

Assume that the counter 8.2 has 8 digits and that its 20 counting capacity ranges therefore from 0 to 255. It follows therefore that 8.7 is high, except when $n = 255$. Consequently, the pulses H arrive generally over 8.4 (unblocked) at 8.8. As soon as S_3 stops, the counter 8.2 counts starting from n: (n+1), (n+2) ... When it attains 255, all outputs are high, 8.4 is blocked, 8.7 goes low and the counter remains in the state 255 up to the next impulse S_3 . Assume also that the repetition period of S_3 in $n_e H$, that is equal to n_e times the clock period H, which period is simply obtained by dividing the clock frequency by n_e by means of a well-known device. Also assume that S_3 has a duration equal to $n_T H$, that is n_T times the clock period. The output 8.7 is then high during a time t_H , where

$$t_H = n_T H + (255-n)H,$$

or more generally, $t_H = n_T H + (255-n)H$. If N is the capacity of 8.2, the ratio t_H divided by the repetition frequency of the phenomenon is thus:

$$n = \frac{n_T H + (N-n)H}{n_e H} = \frac{n_T + N-n}{n_e} = A-B_n$$

It follows that the simple filtering of the output 8.7 of 8.3 yields a voltage which is a linear function of n and, consequently, that its mean value is equal to the mean value of the desired regulation.

Formation of the numerical mean.

Referring to FIG. 9, the following is the procedure to obtain the mean value of the function F in numerical 50 form. The clock pulses that exist while S (FIG. 7) is high are counted for a certain number of samplings, for example, for 2^b , and we use for the representation of the value of F only the number of pulses divided by 2^b . That is, we use only the (b+1) first digits of the counter.

The pulses S_1 of the divider of FIG. 1 are directed to a divider 9.1 which divides by 2^b (FIG. 9) which brings the output of a NAND coding gate 9.2 inverted by inverter 9.3 to the high level when it has received 2^b pulses (or another code).

This inverted output from inverter 9.3 is applied to one of the inputs of each of NAND gates 9.4, 9.5, 9.6. To the gate 9.4 is applied at a second input the signal 5, so that a low pulse of duration S_1 appears at its output for all 2^b samplings. This low pulse is applied to one of the inputs of a NAND gate 9.7, which also receives the clock pulses H and the signal S of FIG. 7.

It follows that **H** is present at the output of **9.7** if **S** is high (decoding) and if the output of **9.4** is high. Gate **9.7** is blocked for a duration **S₁**, for all 2^b samplings. The transmitted pulses are counted by the counter **9.8** which divides their number by 2^b and transmits a signal to a counter **9.10** once every 2^b pulses.

It follows that the counter **9.8** marks a number **N** from a zero at the start of a cycle after 2^b samplings

$$N = R_s \times (2^b/2^b) = R_s = F_{mean}$$

The gates **9.5** and **9.6** permit, according to an already described connection, the conditioning of **9.8** and **9.10** at each mean cycle by **S₂** and **9.5** and the transfer of data from the buffer register **9.11** by gate **9.6** and signal **S₃**.

Transformation of the voltage (or code) into a duration.

It can happen that we want to transform the signal **S** of FIG. 7 coded by modulating the cyclical ratio into a time duration, which is, the time of the fuel injection, for example. A circuit for accomplishing this is shown in FIG. 10.

To the base of a transistor **10.1** is applied a positive release signal (connected, for example, to the fuel injection release control mechanism), which makes transistor, **10.1** conductive to discharge a capacitor **10.5** through a current limiting resistor **10.4**, to the emitter potential of **10.1**. The emitter potential fixed by the voltage divider **10.15**, **10.14** is stabilized by a capacitor **10.16**.

The discharge of capacitor **10.5** reduces the voltage at the non-inverting input (−) of an amplifier **10.6** and the output signal of **10.6** increases. This signal is applied to one of the inputs of a NAND gate **10.9**, which receives at its other input the release signal inverted by an inverter **10.17** so that, though the output of **10.6** is high, the output of NAND **10.9** is high up to the end of the release signal, which thus does not have to be accurate in duration. At the end of this signal the output of NAND-gate **10.9** becomes low until the output of amplifier **10.6** goes low.

The foregoing is the case when the voltage of **10.5** is higher than the voltage applied to the non-inverting input (+) of **10.6** from a transistor **10.2**. The latter voltage is obtained by an RC filter **10.12**, **10.11**, connected to the collector of **10.2**, which receives at its base the signal **S** of FIG. 7.

The response of the circuit of FIG. 10 is exponential. That is, for a given variation of **V** according to the absolute value of the latter, the variation of the time is different. This is frequently of interest for an injection circuit, for example, but it is evident that the response can be linearized by replacing **10.3** by a constant current generator.

Transformation into angles.

It can happen that we want to transform the signal **S** into an angle. This is obtained easily by a circuit similar to FIG. 10, except that the resistance **10.3** is replaced by a generator which furnishes a certain amount of voltage each time an angular mark is counted. To facilitate the understanding of this arrangement, we will show in detail how these signals are formed in a specific and rather complex case, from which simple cases can then be deduced. The selected problem is given below.

It is desired to deliver a signal twice per revolution of a motor, for example, signals which will be substantially in diametral opposition, but with an angular position. These signals are a multi-dimensional function of sev-

eral parameters and are to be delivered, for example, over two different paths. This would be the case, for example, in an ignition system for four-cylinder engines without distributor, each signal releasing the ignition in two cylinders controlled simultaneously by the same coil.

The angles can be marked, for example, by counting the teeth of the starting gear of the motor. To this end, as indicated in FIG. 11(a), a sensor is placed opposite said teeth. This sensor can be of any type, optical, with a blocking oscillator, electromagnetic, etc. The gear **11.1** carries a toothed starting ring **11.2** opposite which is placed a proximity sensor **11.3** which delivers signals at its output **11.4**. Also provided is a hole or a slot **11.5**, which can be sensed by a sensor **11.6**, called a synchronization sensor, which delivers a signal once per revolution. The slot **11.5** is put in place before the mechanical balancing of the wheel.

In the case under consideration, an operation is to be effected every half revolution of the engine. The number of teeth **11.2** of a starting device is, in general, a prime number and hence non-divisible by two. It is convenient to first obtain a double frequency, that is a signal each time an angle equal to half the angle of successive teeth is traversed. To this end an evident solution, not shown here, consists in placing two sensors, such as **11.3**, displaced relative to each other by $(n+1/2)\alpha$. Here, α is the angle which separates two consecutive teeth and n is any integral number. The outputs of the two sensors, after adaptation of the impedance if necessary, are coupled to an OR gate, and at the output of this gate appears the signal with the desired frequency.

The same method can be used to obtain a signal with a frequency k times higher than that which is naturally produced by the teeth by displacing k sensors, such as the sensor **11.3**, relative to each other by angles $(n_i + (i-1)/k)\alpha$, with $i = 1, 2, 3 \dots (k-1)$. The first sensor is numbered zero and taken as the origin of the displacements. This permits obtaining a resolving power which is k times more accurate than the natural frequency produced by the teeth.

In the particular case of the selected example, where $k = 2$, we can obtain a satisfactory solution with a single sensor, such as **11.3**, by selecting a sensor of the magnetic type with variable reluctance. This sensor, shown in FIG. 11(b), comprises a magnetic armature **11.8** carrying a double-ended pole piece spaced in an interval equal to that of two consecutive teeth of the wheel. A coil **11.9** is placed around the pole piece and one end is connected, for example, to ground, while the other end **11.4** is free.

The sensor of FIG. 11(b) is inserted into the electronic circuit shown in FIG. 11(c). The coil **11.9** is supplied current through a resistance **11.10** connected to the positive voltage terminal of the installation. The passage of the teeth of **11.2** of the gear produces variations of voltage at the coil **11.9**. The voltage produced varies in correspondence substantially as the minimum and the maximum reluctance conditions of the sensor **11.3**, that is, substantially when the teeth face each other and when the teeth are in maximum angular phase displacement. This undulating voltage is transmitted directly through a resistor **11.11** to one of the inputs of a sum-and-difference amplifier **11.15**. The mean, or average, value of this voltage is applied to the other input through a resistor **11.14**, this value being obtained by an RC filter consisting of a resistor **11.2**

and the capacitor 11.13. The amplifier 11.15 passes then from a high state, for example, to the low state, when the teeth oppose each other, and from the low state to the high state when the teeth are in maximum phase displacement.

The change in state of 11.15 from low to high is derived by an RC circuit 11.20, 11.26 and is transmitted over a diode 11.24 to the base of a transistor 11.28 which is normally blocked by the voltage across a resistor 11.27. A resistor 11.21 permits the discharge of capacitor 11.20 when the output 11.16 of amplifier 11.15 is low. It follows that a short duration low signal is produced at the collector of transistor 11.28 with each change of voltage from low to high at 11.16.

The signal at 11.16 is inverted by a transistor 11.19 applied to its base by resistor 11.17. The signal at 11.16 produced at the collector of 11.19, which is supplied voltage by a resistor 11.18, goes positive each time 11.16 passes from high to low. This signal is used like the direct signal of 11.16, that is, it is derived by an RC circuit 11.29 and applied by a diode 11.23 and a resistor 11.25 to the base of a transistor 11.28. The resistor 11.22 serves to discharge capacitor 11.29, while 11.16 is high. It follows that a short duration low signal is produced when 11.16 passes from high to low. Finally there is produced on the collector of transistor 11.28 a signal with double the frequency of the natural frequency, which is the objective to be achieved.

FIG. 12 shows how the preceding information is used to solve the problem in question. The double frequency pulses formed as in FIG. 11 are applied to the input 12.1 of the circuit shown while the synchronization pulses (assumed negative and of an angular width of less than $\alpha/2$) from sensor 11.6 are applied to the input 12.6 of the same circuit. Element 12.2 is a counter with p digits with a counting capacity of $(2^p - 1)$, when $(2^p - 1)$ is greater than 2ν , where ν designates the number of teeth 11.2.

Element 12.3 is a gate type circuit which delivers to its output 12.41 a negative (low) signal when the outputs of the counter 12.2 pass through a number representing a number predetermined by the internal connections of 12.3. Element 12.4 is similar.

Element 12.3 is coded for a number equal to 2ν . If A is the signal produced by 12.3 at 12.41 and B that applied to a gate 12.5 by the synchronization sensor 11.6, a signal C is present at the output of a gate 12.5, where:

$$C = \overline{A} \cdot \overline{B} = \overline{A} + \overline{B}$$

It follows that signal C becomes high, whether A or B or both become low. This high signal applied to the proper input of counter 12.2 ensures its resetting to zero.

Since the frequency of B after one revolution of the motor, that is, 2ν pulses to 12.1, is the same as that of A (12.3 wired for 2ν) the resetting of 12.2 to zero after at most one revolution of the motor is such at any time that the number appearing at the output of 12.2 is equal to twice the number of teeth passed by after the passage through the position of the slot or hole 11.5 of FIG. 11(a) in front of the sensor 11.6. The output 11.7 of sensor 11.6 is connected to 12.6 as mentioned above.

The signal A is negative and extremely brief, since it causes the resetting of 12.2 to zero and thereby causes its own disappearance over the element 12.3. This negative signal flips an RS type flip-flop circuit consisting of the NAND gates 12.8 and 12.9, this flipping brings

the level of 12.8 high. At the first pulse following the resetting to zero of counter 12.2, the output of its least significant bit (2^0) passes from low to high. This signal (2^0) is applied to an inverter 12.7 which is connected

5 to the second input of NAND 12.9 and causes the flip-flop circuit RS to flip back. It follows that at each revolution of the motor, starting from the angular position of resetting to zero, if we take it as the origin, the output 12.8 moves to high during an angle equal to $\alpha/2$.

10 The device 12.4, similar to 12.3, is coded to a value equal to ν , which has the result that after ν impulses, after the resetting to zero, its output moves down and remains there, until 12.2 counts ($\nu + 1$), that is, during an angular development equal to $\alpha/2$. This signal is inverted by the inverter 12.12.

15 This inverted signal and the signal issuing from 12.8, formed as described above, are applied over diodes 12.13 and 12.14 to the base of a transistor 12.15 so that the latter is made conductive from the position 0 to the 20 position $\alpha/2$ and from the position 180° to the position $(180^\circ + \alpha/2)$. This has the effect of discharging a capacitor 12.28 substantially to the potential of the emitter of 12.15, a potential formed by a divider 12.21, 12.20 stabilized by a capacitor 12.19.

25 To a 12.18 of the transistor 12.17 are applied over a resistor 12.18 from terminal 12.16 rectangular signals whose cyclical ratio is representative of the regulation, for example, those originating from the output 8.7 of 8.3 of FIG. 8(a).

30 This transistor is applied voltage at its collector by a resistor 12.22 connected to the positive terminal of the circuit. An RC filter 12.23, 12.14 supplies the output of 12.17 through a resistor 12.25 to the non-inverting input of an operational amplifier 12.35. The output 35 voltage of 12.17 has a value between the circuit supply voltage applied by a resistor 12.22 and the voltage applied to the emitter of 12.17 from transistor 12.15 and is representative of the mean cyclical value of the signals applied at 12.16.

40 The discharge of capacitor 12.28 causes, as mentioned above, the downward passage of the inverted input (−) of amplifier 12.35 and consequently the upward passage of its output. This state remains as long as 12.15 is conductive, that is, during an angle $\alpha/2$. The capacitor 12.28 is then recharged intermittently in the following manner. With each impulse arriving at 12.1

45 a monostable circuit 12.36 is triggered (represented here as an integrated circuit, which is known). The negative pulses of fixed duration delivered by it are applied over a resistor 12.37 to the base of a transistor 12.34. During these pulses transistor 12.34 is thus blocked, permitting the application to the base of a transistor 12.30 of the high output voltage of amplifier 12.35 over a voltage divider 12.32, 12.33. It follows that, as long

50 as the output of amplifier 12.35 is high, and only during this time, negative pulses of a duration equal to that of the pulses of the monostable circuit 12.36 are applied over a resistor 12.31 to the base of a transistor 12.29, making it conductive by these pulses and charging capacitor 12.28. It follows that from the start of the moment when 12.15 is non-conductive, the voltage applied over 12.37 to the inverted input of 12.35 rises intermittently. When this voltage becomes equal to that applied to the noninverted input, amplifier 12.35

55 switches back.

60 This switching thus produces a number nR of impulses arriving at 12.1, after the end of the conduction.

65

This number n_R depends, all other values being assumed fixed (values of 12.37, duration of 12.36) on the value of the mean voltage produced by the signals supplied at 12.16.

The angular delay introduced is:

$$\Delta\alpha = (\alpha/2) + n_R (\alpha/2) = (n_R + 1) (\alpha/2),$$

since the pulses are separated by angles $\alpha/2$ and the angle of conduction of 12.15 is $\alpha/2$, as explained above.

Finally a signal appears (passage from high to low of the output of 12.35) at the angles $(0+\Delta\alpha)$ and $(180^\circ+\Delta\alpha)$, $\Delta\alpha$ being a function of the program of the memory 8.1 of FIG. 8.

As 12.35 switches back, the feedback resistor 12.50 lowers the potential of the non-inverted input to prevent oscillation of the system. It is possible in another variant, represented by dotted lines, to proceed differently, for example, to bring the inverted input to a high potential, due to the transistor 12.52 which, blocked when the output of 12.35 is low, ensures by resistor 12.53 and the diode 12.55 the high potential of capacitor 12.28. The diode 12.55 avoids any influence during the intermittent charge.

The exploitation of the switching signal of 12.35, given here by way of example, also causes a monostable circuit 12.38 to be triggered when 12.35 switches. The input of 12.38 is connected to 12.35 and delivers at its output a positive signal when triggered. The NAND gates 12.39 and 12.40 driven by the monostable 12.38 permit the signal to be switched over two paths.

At the 0° position, the negative impulse coming from 12.3 at 12.41 causes the RS flip-flop circuit consisting of the NAND gates 12.10 and 12.11 to flip, which produces an upward rise at the output of 12.11. It follows that the signal issuing immediately thereafter ($\Delta\alpha$ later) from monostables 12.38 will pass through 12.39 (NAND gate) and at 180° , the negative pulse issuing from 12.4 at 12.42 will cause NAND-gates 12.10, 12.11 operating as an RS flip-flop to flip. At this time the output of 12.10 will move up which causes in the position ($\Delta\alpha + 180^\circ$) the appearance of the signal of 12.38 (inverted) at the output of NAND 12.40.

The symbolic diagram of FIG. 13 shows, by way of example, a control circuit for the fuel injection time of the car engine. The regulation of the injection time is affected on the basis of information supplied by a speed sensor 13.1, and a pressure sensor 13.2. The former delivers a signal in the form of pulses of variable frequency f_x , the latter a similar signal representative of a voltage V_x . A timing circuit 13.3 corresponding to the circuit of FIG. 1, delivers the signals S_1 , S_2 , S_3 , which are applied to two counting and coding elements 13.4 and 13.5. Element 13.4 is one of the measuring circuits of FIGS. 2, 3 or 4. It delivers at its four outputs binary signals corresponding to a word segment, so that the mean value of this word segment of a certain number of samples is representative of the mean value of the speed measured by the sensor 13.1. Element 13.5 produces a word segment corresponding to the pressure as measured by a voltage and can comprise the circuits of FIGS. 5 and 6.

The two word segments are juxtaposed to constitute a first word applied to the input of the programmed memory 13.6. This programmed memory delivers a second word which can be likewise composed of word segments. For simplification, we assure that the programmed memory 13.6 delivers only one word for the regulation of the injection time.

The second word is applied to a transformation circuit 13.7, which can be that of FIG. 7. This circuit converts the second word into a function S , coded in modulation of the cyclical ratio, whose mean value is representative of the mean value of the desired regulating function.

This function S is in turn converted by a circuit 13.8, which corresponds to that of FIG. 10, into a signal R of the injection time.

Thus, the information supplied at each sampling by the sensors measuring physical quantities connected with the operation of the engine are coded, according to the invention, at a determined sampling frequency each in the form of a number of word segments comprising a limited number of digits. Further, the mean value of several samples of the word segment is representative of the mean value of the corresponding physical quantity. The word segments are grouped to form a first complete word and this first complete word is converted by a programmed memory into a function whose mean value is representative of the mean value of the desired regulating function. This regulating function is converted into a control quantity for the engine.

The sampling frequency is defined by the division of the clock frequency, and the code used is a binary code. The word segments applied to the programmed memory represent the coding of the high order digits of the counted numbers, the low order digits being retained and added to the measuring result in the following sample.

According to the method of interpolation, based on the sampling principle of a physical quantity represented by the duration of a voltage waveform (e.g. a positive pulse), we measure the number of clock pulses emitted during this waveform. Thus, we associate a number n_x of clock pulses with the value x of the quantity.

In order to limit the number of digits of the memory associated with the measuring system, only the high order digits are transferred, the rest remains carried. For example, for a number of impulses $n_x = A_x p + B_x$, where p is an integral number. At the first measurement starting from zero, namely m_{1x} , A_x is transferred and B_x is carried. At the following measurement the reading is: $m_{2x} = n_x + B_x = A_x p + 2B_x$

If $2B_x$ is less than p , A_x is transferred and $2B_x$ is carried. At the i -th measurement, we have

$$m_{ix} = n_x + (i+1) B_x = A_x p + i B_x$$

and if $i B_x$ is higher than p , we have

$$m_{ix} = (A_x + 1)p + (i B_x - p)$$

We transfer then $(A_x + 1)$ and carry $(i B_x - p)$.

It follows from this method that the transfer is sometimes A_x , sometimes $(A_x + 1)$, the mean after a sufficient number of samplings being n_x .

In order to ensure a sufficient control of the engine, in response to several simultaneously measured physical quantities, the invention concerns a control method for internal combustion engines where the information supplied at each sampling by sensors measuring physical quantities connected with the operation of the engine, is coded at the so-called sampling frequency, each in the form of a number of word segments so that the mean value of the word segments from several samplings is representative of the mean value of the corresponding physical quantity. Each word segment represents the coding of the high order digits defined by preselection-counters, the low order digits being re-

tained and added to the measuring results in the following sample. Also, preselected values of counters define the high order digits of each measured physical quantity as prime numbers.

In FIG. 14 a gate 14.1 receives at one of its inputs 14.2 a rectangular waveform signal of a duration proportional to the quantity x to be measured. The other input 14.3 receives clock pulses. The output signals produced by the gate 14.1 are applied to the counting input 14.6 of a preselection counter 14.4. The outputs of the counter 14.4 are applied to a known coding device 14.5, a so-called looping device. When the number counted in 14.4 attains a predetermined value p , the device 14.5 delivers at its output 14.8 a signal applied at 14.7 to the counter 14.4 to reset it to zero, and the signal is also applied to the counting input of a counter 14.9. Counter 14.9 has its outputs 14.11 connected to the rest of the computer and it is reset to zero by a signal applied to its input 14.10 between two samplings. The counter 14.4 is not reset to zero between samplings.

B_{ox} is the value appearing at the outputs of the counter 14.4 at the start of a sample comprising $(A_x p + B_x)$ pulses. At the end of the sampling, the counter 14.11 marks the transfer value, A_x or $(A_x + 1)$, depending on whether $(B_{ox} + B_x)$ is higher or lower than p . The counter 14.4 marks the carry value $(B_{ox} + B_x)$ and $(B_{ox} + B_x - p)$ respectively.

In the case of two quantities to be measured, these can be expressed by:

$$n_x = A_x p + B_x$$

$$n_y = A_y q + B_y$$

With the point n_x , n_y is associated with point Z_{Ax} , A_y , so that the value of z is that associated by the memory with the couple (A_x, A_y) . This can pose a determination problem. In order to facilitate the understanding, we assume that $B_x = p/2$ and $B_y = q/2$. It follows that the transfer n_x is in one case out of two A_x , and in one case out of two $(A_x + 1)$. In the same way, y is measured by an alternate transfer of A_y and $(A_y + 1)$. The mean value of z is then:

either that of the means between Z_{Ax} , A_y and $Z_{(A_x+1)}$,

if the changes are made at the same time, or

the mean between: $Z_{Ax, (A_y+1)}$ and $Z_{(A_x+1), (A_y+1)}$ if the changes are in phase opposition.

Generally speaking, if a value of n_x corresponds to a measurement comprised between A_x and $(A_x + 1)$, and a value of n_y corresponds to a measurement comprised between A_y and $(A_y + 1)$, the associated mean value of z , after a sufficient number of samplings is undetermined. That is, it is inside the tetrahedron defined by the points:

$$A_x, A_y, Z_{Ax}, A_y; A_x, (A_y+1), Z_{Ax}, (A_y+1)$$

$$A_x+1, A_y, Z_{(A_x+1)}, A_y; A_x+1, A_y+1, Z_{(A_x+1)}, (A_y+1)$$

In other words, we associate with each couple of values of n_x and n_y , such as the means of the transfers (A_x+1) , A_x and of values comprised between the planes of the tetrahedron. In general the mean value of z is that obtained by the mean of the values of all possible couples A_x, A_y except in the cases indicated above where we always obtain one or the other of the possible extreme values, depending on the phase of the measurements.

In order to avoid such a phenomenon, it suffices to select the values of p and q conveniently.

In fact, a measurement m_x (or m_y) shifts at each sampling with regard to the transfer value from a quantity B_x/p or B_y/q . It follows therefore that the measurements of the two quantities x and y shift with regard to each other from a quantity

$$\frac{B_x}{p} - \frac{B_y}{q}$$

in each sampling.

If the two measurements do not shift with regard to each other, we can obtain the highest phenomenon, that is, the interpolation couples do not vary in time but can be different according to the phase, that is, depending on the initial state.

The shift

$$\frac{B_x}{p} - \frac{B_y}{q}$$

is evidently zero if $B_x = B_y = 0$. This means that the values correspond exactly to transfer values. There is therefore no uncertainty. On the other hand if B_x , B_y are not simultaneously zero, there is shifting except if $B_x \cdot q = B_y \cdot p$ or $q/p = B_y/B_x$. For forces shifting it suffices that this equality can not be verified. Or p, q, B_y, B_x are integral numbers and $B_x < p$, $B_y < q$.

For example, if $q = 27$ and $p = 9$, $q/p = 3$, we have a phenomenon similar to that indicated above. By way of example, if $B_y = 3B_x$, or for a whole series of values

$$\begin{array}{ll} B_x = 1 & B_y = 3 \\ B_x = 2 & B_y = 6 \\ B_x = 3 & B_y = 9 \\ B_x = 4 & B_y = 12 \\ B_x = 5 & B_y = 15 \text{ etc...} \end{array}$$

The phenomenon can also be produced if q/p is a rational fraction, for example, $q = 82$, $p = 6$, $q/p = 32/6 = 16/3$ we have a phenomenon for $B_x = 3$ and $B_y = 16$.

For this phenomenon not to be possible it suffices that q/p can not be expressed in the form of an integral number or of a rational fraction, that is, that p and q are prime numbers.

In the case of a system with more than two quantities, it suffices that the division factors $p, q, r, s, \dots$ which have the meaning of p and q in the two preceding examples with two variables, are prime numbers so that any fraction formed by any two of these numbers, taken two by two, is irrational.

According to the invention, in the case where several devices of this type are used simultaneously for measurements $n_x, n_y, \dots$, the counters of the type 14.4, which exist for each measurement, are looped around predetermined values, $p, q, r, \dots$, which are prime numbers.

Generally speaking, the signal corresponding to the desired regulating function is converted into a signal with the duration of one waveform into a signal corresponding to an angle of rotation of the engine.

It should finally be pointed out that the second word, delivered by the programmed memory, can consist of several word segments each corresponding to a regulating function of the operation of the engine or to a control function of an accessory of the engine or of the vehicle equipped with an engine. These different word

segments are converted each by an independent electronic chain.

In the embodiments previously described, the analogous voltage representative of the linear function is obtained by means of an RC-filter.

Another object of the present invention is to form from the said linear function a non-linear function representative of the desired regulating function. It concerns a control system and method for internal combustion engines in which physical quantities connected to the operation of the engine are coded in the form of word segments grouped to form a first word. The first word is converted by a programmed memory into a second word, which is converted in turn by a transformation circuit into a linear function, and coded in modulation of the cyclical ratio. This linear function is transformed into a non-linear function corresponding to the desired regulating function.

The curve representing this non-linear function consists preferably of straight-lined segments. Referring to FIG. 15, the first line shows a signal A for resetting the counters to zero, which is high during the short resetting period and low during the rest of the time. The second line represents the transfer signal Tr or the signal for charging preselection counters, and the third line represents the output signal N of preselection counters. By convention, the output signal N is high when the counters are not saturated (below the preselected counting level) and low when they are saturated.

The frequency of the latter signal is that of the sampling and is obtained by numerical division of the clock frequency. The division is so effected that the sampling period, that is, the repetition period of the signal, expressed in number of clock pulses, is at least equal to and generally higher than the maximum capacity of the preselection counter(s). The length, expressed in the number of clock pulses of the high part of the signal of the third line depends on the charge value of the counters, that is, on the word present at the output of the matrix at the time of transfer.

If this length is designated with N (n being the number of clock impulses which measures it) and if an RC-filter is placed at the output of the signal, we obtain at the output of the filter a voltage V, proportional to the supply voltage and proportional to N. This is shown in FIG. 16.

According to the present improvement, it is suggested to realize a curve of V as a function of N as shown in FIG. 17, that is, instead of obtaining a straight line passing through the origin of the plane (N, V), we suggest to obtain a value V = E1 for N = 0 (N can evidently not assume negative values). V = E2 for N = 1, V increasing linearly from E2 to E3 for N varying from N = 1 to N = Nr, then linearly along another slope from E3 to E4 for N between Nr and Nm.

To this end we use the circuit of FIG. 18. A bistable flip-flop circuit FF of the RS type is supplied by the signal A at one of its inputs R after being differentiated by the element d/dt , so that the output signal of this flip-flop circuit moves upward at the time of the appearance of the signal A (positive leading edge on the first line in FIG. 15). This same flip-flop circuit is supplied at its other input S by the signal N, that is, the complementary signal of $\bar{N}$ (3rd line of FIG. 15).

The circuit comprises three transistors T1, T2, T3, whose emitters are connected to the ground. Between the voltage source E and the collector of T1 are ar-

ranged two resistors R1 and R2 in series. The output signal is taken from their common point. The output of the flip-flop circuit FF is connected to the base of T1.

A circuit consisting of a resistor R3 and of a transistor T2 is connected in parallel to R2 and T1. The base of T2 receives the signal $\bar{N}$. A circuit consisting of a resistor R4 and of a transistor T3 is connected in parallel to T2. The base of T3 receives the signal N_r . Finally, a resistor R5 is connected in parallel to T3.

The sampling period is obtained by numerical division of the clock frequency. From the divider described in FIG. 1 is taken an output signal which goes high, for example, when N_r clock impulses have elapsed from the time of the signal TR (this circuit is not shown, because it is conventional. For different values of N the output signal is represented in FIG. 19.

The operation of the circuit of FIG. 18 is as follows:

output FF high	T1 conductive
output FF low	T1 blocked
N high ($\bar{N}$ low)	T2 blocked
N low ($\bar{N}$ high)	T2 conductive

Number of clock impulses from Tr less than N_r : T3 conductive.

Number of clock impulses from Tr higher than N_r : T3 blocked.

At the transfer time T1 becomes thus conductive (flipping of FF) and remains conductive if $N = 0$, or it is immediately blocked if N is greater than or equal to 1 (immediate flopping of FF).

The regulation of the device is effected as follows:
a. The transistor T1 is kept blocked and the transistors T2 and T3 are kept conductive by means of a positive voltage applied to their bases. The voltage V_s is then equal to

$E \cdot R3/(R1 + R3)$, if E designates the supply voltage
R3 is regulated as follows, R1 being assumed non-adjustable:

$V_s = V2$ (R4 and R5 short-circuited by T2 have no effect).

b. T3 is kept conductive and T2 is blocked. We have then (since T1 is always blocked):

$$V_s = \frac{ER3 + R4}{R1 + R3 + R4}$$

R4 is adjusted so that this value is always equal to the desired value $V3$

c. T1 as well as T2 are kept blocked and T3 is blocked.

We have then:

$$V_s = \frac{ER3 + R4 = R5}{R1 + R3 + R4 + R5}$$

R5 is adjusted so that this value is equal to $V4$.

d. T1, T2 and T3 are made conductive so that we have:

$$V_s = \frac{R2 \cdot R3}{R1 + \frac{R2 \cdot R3}{R2 + R3}}$$

R2 is adjusted so that this value is equal to V1. The curve of FIG. 17 is obtained after filtering the signals of FIG. 19 through an RC-circuit.

According to the invention, a non-linear function with more than two straight-lined portions of different slopes can be provided.

The non-linear function is realized by modulating the amplitude of the signal with a variable cyclical ration as a function of the code of the second word.

What is claimed is:

1. A control system for an internal combustion engine including at least two sensor means for respectively producing information corresponding to physical quantity representations of operating conditions of the engine comprising, means for sampling the information supplied by a respective sensor means at a predetermined frequency, means for coding each of the respectively sampled informations into a word segment having a limited number of digits, the mean value of the word segments from several samplings being representative of the mean value of the corresponding physical quantity, means for grouping the word segments to form a first complete word, programmed memory means for converting the first word into a second word, means for transforming the second word into a function whose mean value is representative of the mean value of a desired regulating function for the engine, and means for converting the regulating function into a control quantity for the engine.

2. A system as in claim 1 wherein each of said word segments represents a number.

3. A system according to claim 1 wherein the coding means produces word segments corresponding to a linear function of the respective conditions sensed by said sensor means.

4. A system according to claim 1 wherein the coding means operates in each sampling to produce a word segment representing the coding of more significant digits and retains the less significant digits for adding to the result of the next sampling.

5. A system according to claim 4 wherein the sensor means produces pulses as the information which are of a frequency of the same order of magnitude as the sampling frequency, and means for storing the information supplied by the sensor during the duration of a sampling and adding the stored information to the result of the measurement in the following sampling to eliminate a stroboscopic effect.

6. A system according to claim 1 wherein the sensor means produces pulses as the information which are of a frequency which is higher than that of the sampling frequency, said coding means word segments indicating a numerical value and said coding means operating to carry a retained numerical value and displacing the zero.

7. A system according to claim 1 wherein the sensor means measures a voltage, said coding means word segments indicating a numerical value and said coding means operating to carry a retained numerical value and displacing the zero.

8. A system according to claim 1 wherein the transforming means for producing the mean value of the function operates independently of the sampling frequency.

9. A system according to claim 8 further comprising preselection counter means for selecting a portion of the word segments produced and wherein the trans-

forming means includes means for producing the mean value of the function by filtering the output signal of the preselection counter.

10. A system according to claim 8 wherein said sampling means includes means for producing clock pulses at a predetermined frequency, said transforming means producing the mean value of the function in numerical form by dividing the number of clock pulses by the number of samplings.

11. A system according to claim 1 further comprising means for converting the signal corresponding to the regulating function into a signal having a waveform with a determined duration.

12. A system according to claim 1 further comprising means for converting the signal corresponding to the regulating function into a signal corresponding to an angle of rotation of the engine.

13. A system according to claim 1 wherein, the second word produced by the programmed memory means includes several word segments each corresponding to a regulating function of the operation of the engine.

14. A system according to claim 13 wherein at least one of the word segments of the second word corresponds to a control function of an accessory of the engine.

15. In a control system for an internal combustion engine including at least two sensor means each for producing information corresponding to respective physical quantity representations of operating conditions of the engine comprising, means for sampling the information supplied by the sensor means at a predetermined frequency, means for coding each of the respectively sampled informations into a word segment having a number of digits, said coding means operating so that the mean value of the word segments from several samplings is representative of the mean value of the corresponding physical quantity, said coding means including preselection counter means for selecting the portion of the word segment representing the coding of the most significant digits at a preselected value which is related to prime numbers, said coding means retaining the low order digits and adding them to the result of the following sampling.

16. In the system according to claim 15 further comprising looping means connected to said preselection counter means, said looping means applying a zero-resetting signal to the preselection counter means when the latter has counted a number equal to the preselected value.

17. In the system according to claim 16 wherein there are a plurality of preselection counter means each for measuring information from a respective means corresponding to a physical quantity each said preselection counter means operating at a preselected value related to at least one prime number.

18. In the system as in claim 15 wherein each of said word segments represents a number.

19. A control system for an internal combustion engine including at least two sensor means each for producing information corresponding to respective physical quantity representations of operating conditions of the engine comprising, means for sampling the information supplied by the sensor means at a predetermined frequency, means for coding each of the respectively sampled informations into a word segment, means for grouping the word segments to form a first

word, programmed memory means for converting said first word into a second word, means for transforming the second word into a linear function coded by a cyclical ratio, and means for converting said linear function into a non-linear function corresponding to a desired regulating function for the engine.

20. A system according to claim 19 wherein said means for producing the non-linear function produces a function having a constant level, a first straight-lined portion with a given slope, and a second straight-lined portion with a different slope than said first straight-lined portion.

21. A system according to claim 20 wherein the constant level portion of the function corresponds to a code of the second word equal to zero, the first straight-lined portion to a code ranging from one to a predetermined fixed code, and the second straight-lined portion to a remaining code.

22. A system according to claim 21 wherein the non-linear function producing means includes means for modulating the amplitude of the information signal from a sensor means with a variable cyclical ratio as a function of the code of the second word.

23. A system according to claim 20 wherein the means for producing the non-linear function comprises a first transistor, connected between a feed source and a reference potential point in series with two resistances whose common point constitutes the output terminal of the circuit; a second transistor connected in series with a third resistance between the said output terminal and the reference potential point; a third trans-

sistor connected in series with a fourth resistance between the reference potential point and the common point at the second transistor and at the third resistance; a fifth resistance being connected in parallel with the said third transistor.

24. A system according to claim 23 wherein said coding means includes a resettable preselection counter means for selecting the portion of the word segments representing the most significant digits of the word segments and wherein the base of the first transistor is connected to the output of a bistable flip-flop circuit whose first input receives a signal at the frequency of the variable cyclical ratio before the preselection counter is reset which serves to obtain the variable cyclical ratio, and whose other input receives the complementary signal of the variable cyclical ratio supplied by the preselection counter, this signal existing only if the code of the second word is different from zero.

25. A system according to claim 23, wherein the base 20 of the second transistor receives the complementary output signal of the preselection counter.

26. A system according to claim 23, wherein the base 15 of the third transistor receives the complementary signal with a predetermined fixed cyclical ratio corresponding to the predetermined fixed code.

27. A system according to claim 20 wherein the said non-linear function comprises more than two straight-lined portions with different slopes.

28. A system as in claim 14 wherein each of said 30 word segments represents a number.
